UNITED STATES PATENT OFFICE

156,279

DESIGN FOR A MILK DISPENSING CABINET

Leonard B. Rasmusson, Minneapolis, Minn., assignor to U. S. Thermo Control Company, Minneapolis, Minn., a partnership

Application February 25, 1948, Serial No. 144,719

Term of patent 14 years

(Cl. D2—3)

To all whom it may concern:

Be it known that I, Leonard B. Rasmusson, a citizen of the United States, residing at Minneapolis, county of Hennepin, and State of Minnesota, have invented a new, original, and ornamental Design for a Milk Dispensing Cabinet, of which the following is a specification, reference being had to the accompanying drawing, forming a part thereof.

Fig. 1 is a front elevational view of a milk dispensing cabinet, showing my new design;

Fig. 2 is a perspective view showing the front, top and one side of my dispensing cabinet;

Fig. 3 is a side elevation, and

Fig. 4 is a top plan view of said cabinet.

I claim:

The ornamental design for a milk dispensing cabinet, as shown.

LEONARD B. RASMUSSON.
